C A R L W E I D L I N G, O F N E W Y O R K, N. Y.

Letters Patent No. 90,975, dated June 8, 1869.

IMPROVED FIRE-ESCAPE LADDER.

The Schedule referred to in these Letters Patent and making part of the same.

To all whom it may concern:

Be it known that I, C A R L W E I D L I N G, of the city of New York, in the county and State of New York, have invented certain new and useful Improvements on the Machine known as an "Improved Fire-Escape," which was duly patented, and for which Letters Patent were granted, and issued by the Government of the United States of America, under the seal thereof, to Carl Weidling, Alexander Lieder, and Charles Kunkel, assignees of myself, the said C A R L W E I D L I N G, on the 30th day of July, 1867, (Letters Patent, No. 67,239;) and I do hereby declare that the following is a full, clear, and exact description of the construction and operation of the same, reference being had to the annexed drawings, making a part of this specification, in which—

Figure 1 represents the horizontal and side view of wagon, the former showing the iron ring (colored blue) which allows the fore part of truck to turn at right angles, to facilitate transportation when in actual operation in and out of and around the corners of narrow streets.

A B, a reach, fastened at A, but moving freely right and left, at B, in the hind axle for that purpose.

D, wooden frame of truck.

E E E E are four levelling-screws, to adjust the new turning-table, fig. 2, to a level, when the wagon is on uneven or broken ground.

F, chain and hook, to be attached to a hand-screw, and hook, R, fig. 3, when apparatus is fully extended, to bind the platform more securely to the wagon.

Figure 2 represents the turning-table—horizontal and sectional view. The turning-table rests on the wagon, by means of which the platform, fig. 3, and the ladders, when extended, can be moved on the iron circles to face in any direction, without moving the wagon.

Figure 3 represents the platform and triangle, to which the ladders are attached.

G G G are hinged joints, secured by bolts or springs.

H H are folding extension-arms, with the adjusting-screws a a a a, which reach the ground to make the whole apparatus steady when in use. (See fig. 7.)

J J, timber frame of platform.

I I, timber frame of triangle.

K, spring-hook, to hold secure all hinged joints instead of bolts.

Figure 4 represents the front view of the triangle.

M N N O O K K, windlass, and its machinery.

P, roller, over which the hoisting-ropes Q Q move. Said ropes or chains being fastened near the top of the lower ladder, also attached to the end lever Z, (see fig. 6,) the other end to the windlass M, serve to bring the ladders from a horizontal position to the position shown in fig. 6.

Figure 5, side view of triangle and lever Z.

S, brace of wood.

T, folding brace.

V, hinge, secured by bolt or spring in rear.

Instead of folding brace, a straight brace, secured by iron at top, can be used, fastened at lower end by a spring on the platform J J.

X, iron cradle, wherein moves, and which secures the movable lever Z to platform J.

Figure 6 represents side view of apparatus, showing the ladders elevated by means of ropes or chains Q Q, and lever Z and windlass M on triangle.

A is an iron cradle, which secures an iron axle, on which the ladders and the folding brace T are secured.

E is a movable prop or support, attached to the upper part of lower ladder by a drop-bolt, and the lower end resting on the ground, when apparatus is in use.

g is a check-rope or chain, secured to the top of lower ladder and to platform, to prevent the ladders being forced backward out of the perpendicular by rope Q.

f is an iron fastening, whereto is attached the reach of rear wheels when being moved from place to place, in use or in transportation.

S, hinge, on upper ladder, to allow same, when elevated, to form a bridge.

N, hand-rope, by which upper ladder is elevated, when required.

O, spring-hook, to fasten to ring P, to retain ladder in position when elevated.

R, hinged beam, with hand-screw and hook, to secure platform more effectually to wagon, in connection with the chain and hook F. (See fig. 1.)

Figure 7 represents front view of apparatus, partly extended.

d, d are wooden props, permanently fastened to lower ladder by rings e e, and secured, when apparatus is in use, to the end of folding arms H H, in cradles b b, by movable pins, c c.

F, windlass and gearing, placed on and at the bottom of lower ladder, to which ropes or chains, L L, are attached, passing over a roller at the top of lower ladder, and fastened to the bottom of second ladder.

M M, ropes or chains, fastened at the top of lower ladder, passing over a roller at the top of second ladder, and secured to the foot of third ladder, by means of which ropes, so fastened, and the operation of the windlass F, the three ladders rise simultaneously.

Figure 8 represents the ladders and props, detached from platform.

Figure 9 represents a cross-section of the ladders through line A B of fig. 8.

Figure 10 represents a cross-section of the ladder through line C D of fig. 8.

The ladders consist of several distinct parts, a b c d, the side pieces of which are grooved, so that one slides in the other.

Figure 11 represents the apparatus folded up in

readiness for use and transportation, showing the triangle I lifted up. Position the folding brace T as angle I assumed, as also the movable lever Z.

C is a reach, attaching rear wheels to platform, secured by linchpin.

On the axle of rear wheels, and also on end of platform, are placed rollers, h, on which the props or supports E are placed, when detached from the ladder for transportation.

Figure 12 represents the ladder fully drawn out and in use, with the fourth ladder or bridge bent at hinge T, whereby the same may be fastened to the roof in windows of a building.

Q are two iron bars, fastened on each side of the third ladder, and outside thereof, and raised or lowered by the chain R, by hand, to give additional strength to the apparatus when leaning against a building.

In the upper part of third ladder are placed two iron rollers, U, at right angles, on which a rope, V, works, to which is attached a large canvas bag, W, for the purpose of saving persons or property, which may be placed therein and lowered to the street.

X is a rope, placed at the bottom of said sack, to direct its descent.

Z is a hose and pipe, which can be fastened to and raised with ladders.

The apparatus is constructed of wood and iron, and is self-supporting, when extended to its full height.

Each of the said windlasses is connected with cranks, gearing-wheels, and ratchets, so that they may be turned or stopped at pleasure. The whole apparatus may be turned to any required direction on the turntable.

When the apparatus is in the position shown by fig. 6, and the windlass is turned to the right, the ladders will simultaneously slide upward, until the whole apparatus is elevated to its greatest height, as shown in fig. 12. When in that position they may be lowered down again by turning the windlass to the left, when all the parts will slide downward.

To make the apparatus ready for transportation, reverse the windlass in the triangle, having first placed the rear wheel in position, lifting the props E E from the ground, and the ladders will assume a horizontal position, resting on said rear wheels. Then detach the props E E, and place them under the ladders. Take out the pins from the ends of the props d d, and lay them side of ladders. Unfasten the bolts or springs of the arm H H, so named in fig. 6, and lay them over the ladders. Then withdraw the bolts or springs on triangle and jointed brace, and by means of windlass on triangle, turn the said triangle over on ladders also, as seen in fig. 11. To elevate, reverse the above.

Having thus described my invention,

What I claim as new, and desire to secure by Letters Patent, is—

The combination, with the said ladder and turntable, of adjusting-screws, by means of which the elevating-frame, to which the ladder is attached, may be levelled, and firmly supported, substantially as hereinbefore set forth.

CARL WEIDLING.
